IMPACT TESTING MACHINE

Nathaniel Warshaw, Boston, and Henry B. Shepard, Newton, Mass., assignors to Stowe-Woodward, Inc., Newton Upper Falls, Mass., a corporation of Massachusetts

Application August 5, 1933, Serial No. 683,782

4 Claims. (Cl. 73—51)

The principal object of our invention is to provide a machine having striking means to give blows of the same force simultaneously for purposes of comparison, such blows, in the preferred form, being struck on two different golf balls, base balls or the like to determine which is the better ball in respect to carrying power, durability and in any other desired respects, the purpose of simultaneity being to ensure the same conditions such as weather and wind for testing of both objects such as golf balls.

Another object is to use different heads for two strikers to give blows simultaneously on two objects of the same construction to determine the relative merits of the heads.

Another object is to provide a portable machine which may be readily moved from place to place, especially outdoors.

Other objects will be pointed out below.

20 In the drawings

Figure 1 is a front elevation of a machine embodying our invention;

Figure 2 is a section on line 2—2 of Figure 1;

Figure 3 is a plan section on line 3—3 of Figure 1;

Figure 4 is a partial elevation showing different positions of one of the driving members;

Figure 5 is a detail showing the driving member in a different position radially than its position in Figure 4;

Figure 6 is a section on line 6—6 of Figure 1; and

Figure 7 is a section on line 7—7 of Figure 4.

The frame of the machine comprises two side pieces 1 and 2 and base 3 (broken away). Bolts 4 hold the support 5 to base 3. Suitably fixed to the support, as by welding, are blocks 6 and 7 upon which are mounted rubber cups 8 and 9 to receive and hold golf balls 10 and 11 which are of different construction for the purpose explained above.

Mounted to rotate in the side frames 1 and 2 is a shaft 12 having counterweight 13 to balance the strikers described below. Fixed to shaft 12 is gear 14 driven by gear 15 on motor shaft 16 of motor 17, the latter being controlled by switch 18. Belt 19 is driven by pulley 20 on shaft 12 and drives pulley 21 operatively connected to speedometer 22.

50 Studs 23 and 24 are suitably fixed to shaft 12. Slidably mounted on studs 23 and 24 are sleeves 25 and 26 to which are clamped at 27 and 28 the shanks 29 and 30 of strikers 31 and 32, the main portions of the strikers being preferably of steel but having preferably aluminum heads 33 and

34 suitably connected to said main portions, each striker being of the same material and the same weight and of the same form and construction as the other as to all of its parts including its head.

5 Sleeves 25 and 26 are connected by integral bridging portion 35. Shaft 36 is mounted to rotate in ears 37 and 38 rigidly connected with, and consequently always rotating with, shaft 12. Fixed to shaft 36 is latch 38', which, in the full line position of Figure 2, locks the bridging portion 35 and sleeves 25 and 26 in their inner radial position. At the right end of shaft 36 in Figure 3 is integral trip member 39 and integral finger 40, spring 41 tending to hold trip member 39 in the position of Figure 6, the finger 40 bearing against the periphery of shaft 12 to hold the trip member in said position during the rotation of the heads 33 and 34 free of objects 10 and 11.

10 Mounted in said frame 2 is plunger 42, normally held in the position of Figure 1 by spring 43. When the strikers have reached the desired speed as indicated by the speedometer 22, the plunger 42 is pressed by hand to the left in Figure 1 and 3 bringing the rubber collar 44 into the path of trip member 39, turning the latter and shaft 36 and consequently throwing the latch 38' into the dotted line position of Figure 2, thus freeing the sleeves 25 and 26 so that,

15 under the influence of centrifugal force, said sleeves move radially outward until their integral collars 45 and 46 engage rubber collars 47 and 48, as shown best in Figure 2. These rubber collars rest against steel collars 49 and 50, all of said collars being frictionally held on their studs, the head 51 of stud 23 preventing undesired removal of the collars 47 and 49, a similar head 52 being provided on stud 24. Springs 53 are

20 connected at one end with portion 13 and at the other end with bridge 35 and act to retard the outward radial movement of the sleeves 25 and 26 and act also to return the sleeves to inner radial position as the machine slows down after the strikers have acted, this slowing down following the shutting off of the motor.

25 Our machine may also be used to test different heads, such as heads of different golf clubs, by connecting such heads to the two strikers and then simultaneously applying blows to objects of the same structure to determine the relative merits of such heads.

30 In using our machine the motor is started and the strikers are rotated until the desired speed is indicated by the speedometer, the strikers

during this rotation passing freely over the golf balls 10 and 11, as shown in Figure 4 in dotted lines. When the desired speed is attained, the plunger 42 is moved to the left in Figure 1 so as to come into the path of the trip member which is then turned and consequently releases latch 38' permitting the sleeves 25 and 26 and the strikers to move radially outward so as to be in position to strike blows on the golf balls, as shown in Figure 5 and as indicated by the lower dot and dash line in Figure 4. The latch 38' is preferably released just after the strikers have passed freely over the golf balls so that nearly an entire revolution is available for the strikers to move from their inner to their outer radial positions. When the blows have been struck the motor is shut off, and while the machine is coming to a stop springs 53 will return the sleeves and strikers to their inner radial position and the bridging portion will be again latched because of the spring 41 returning the trip member to normal position.

It will be observed that we provide a very accurate test as to different golf balls and the like not only because the blows are struck simultaneously but because the blows are of the same force for the reason that the strikers are of the same weight, material, shape, construction and stiffness and the blows are given at the same speed.

What we claim is:

1. A testing machine comprising a shaft; two strikers; means to rotate said shaft; means connecting said shaft and strikers to cause said strikers to rotate free of certain objects when the shaft rotates but with provision to permit movement of the strikers outwardly radially of the shaft; and means to act on said connecting means to permit such radial movement of

the strikers simultaneously so that the strikers strike said objects simultaneously.

2. A testing machine comprising a shaft; two strikers; means to rotate said shaft; means connecting said shaft and strikers to cause said strikers to rotate free of certain objects when the shaft rotates but with provision to permit movement of the strikers outwardly radially of said shaft; a latch member engaging said connecting means to hold the strikers in their inner radial position; and means to release said latch to permit simultaneous outward radial movement of said strikers.

3. A testing machine comprising a shaft; two strikers; means to rotate said shaft; means connecting said shaft and strikers to cause said strikers to rotate free of certain objects when the shaft rotates but with provision to permit movement of the strikers outwardly radially of said shaft; a latch member engaging said connecting means to hold the strikers in their inner radial position; means to release said latch to permit simultaneous outward radial movement of said strikers; and springs operatively connected with said strikers to retard their outward radial movement and to cause their inward radial movement.

4. A testing machine comprising a shaft; a striker; means to rotate said shaft; means connecting said shaft and said striker to cause said striker to rotate free of a certain object when the shaft rotates but with provision to permit movement of the striker outward radially of the shaft; and means to act on said connecting means to permit such radial movement of the striker so that the striker may strike said object.

NATHANIEL WARSHAW.
